GOLF PUTTER HEAD

Ivan M. Meissler, 82 Homer St.,
Providence, R.I. 02905

Filed Mar. 19, 1974, Ser. No. 452,541

Term of patent 14 years

Int. Cl. D21—02
U.S. Cl. D34—5 GH

FIG. 1

FIG. 2

FIG. 3

FIG. 4

FIG. 5

FIG. 6

FIG. 1 is a front elevational view of a golf putter head showing my new design;

FIG. 2 is a right end elevational view thereof;

FIG. 3 is a left end elevational view thereof;

FIG. 4 is a front elevational view thereof;

FIG. 5 is a top plan view thereof; and

FIG. 6 is a bottom plan view thereof.

I claim:

The ornamental design for a golf putter head, substantially as shown.
